UNITED STATES PATENT OFFICE.

WILLIAM P. STRAWMYER AND OTTO NILIUS, OF INDIANAPOLIS, INDIANA.

RUBBER-TREAD HORSESHOE.

SPECIFICATION forming part of Letters Patent No. 644,879, dated March 6, 1900.

Application filed January 2, 1900. Serial No. 72. (No model.)

To all whom it may concern:

Be it known that we, WILLIAM P. STRAWMYER and OTTO NILIUS, citizens of the United States, residing at Indianapolis, in the county of Marion and State of Indiana, have invented certain new and useful Improvements in Horseshoes, of which the following is a specification.

Our invention relates to that class of horse-shoes which are composed of several parts and in which a portion is made of yielding material, so that the shoe is both easier upon the horse's foot and maintains a better hold upon smooth or slippery surfaces.

Said invention consists in a peculiar construction and arrangement of parts whereby they are properly secured together and in place and given the requisite strength and proportion, all as will be hereinafter more particularly described and claimed.

Referring to the accompanying drawings, which are made a part hereof and on which similar reference characters indicate similar parts, Figure 1 is an upper side plan view of a horseshoe embodying our said invention; Fig. 2, an under side plan view showing that surface which comes in contact with the ground, a part of the outer metal portion being broken away; Fig. 3, a view in the same position as Fig. 2 with the outer metal and rubber portions removed, showing a plan view of the inner metal and leather portions; Fig. 4, a vertical sectional view as seen from the dotted line 4 4 in Fig. 2, and Fig. 5 a detail sectional vertical view as seen from the dotted line 5 5 in Fig. 2.

Our improved shoe is composed of four principal parts. The part A, which comes in contact with the horse's hoof, is preferably formed of sole-leather. Upon this is preferably a sheet-metal stiffening plate or spring B. Secured to the leather portion A and covering the plate or spring B is a part C, of yielding material, preferably rubber. Outside and inclosing a considerable portion of the part C is a metal part D, which in many respects compares in shape and character with the major portion of an ordinary horseshoe.

The parts A and B are first preferably riveted together by rivets r. The part A forms a complete base for the shoe structure upon which the others parts are placed in building

the shoe. The part B is comparatively narrow for the greater portion of its length, but at the ends, immediately within the heel portions, it is enlarged or widened out for the purpose of giving strength and stiffness at this point, over which the outer part D is not intended to extend.

The part C is of a peculiar form. It is, generally speaking, of substantially the shape of an ordinary horseshoe. Its rear or heels are raised or thickened, as at c, so that they extend above or beyond the outer metal portion D when the parts are assembled and come in immediate contact with the ground. Around the outer rim of this rubber portion is a flange f, which is formed integrally therewith, and its inner side is beveled or also somewhat flange-like in form. This is to provide a convenient and efficient means of attachment between the leather portion A and this rubber portion C, which attachment is effected by a row of stitching s, which extends around the outer edge through the flange f, and thence around the ends and inner edge, as shown. This part C has a recess and incloses the part B.

The outer metal portion D, as before stated, is in its general form much the shape of an ordinary horseshoe. It is placed around the outer edge and upon the outer side of the structure, covering the flange f of the rubber and protecting its outer edge. At its rear ends it extends up slightly onto the heel portion of the rubber part, said heel portion being for this purpose given a roof-like form at this point, as best shown in Fig. 5, and this metal part being formed correspondingly to fit onto the corresponding faces of said heel portions. As will also be observed, especially in said Fig. 5, the outer metal portion at this point slightly overlaps the stiffer widened or strengthened rear ends of the metal part B, so that although the rubber is exposed and comes in contact with the surface over which the horse is traveling it is still rigidly and strongly supported.

Having thus fully described our said invention, what we claim as new, and desire to secure by Letters Patent, is—

1. A horseshoe composed of an inner non-metal part, which bears against the horse's hoof when in position, a stiffening part B secured thereto, a non-metal adhesive part C

having a flange *f*, and an outer metal part placed upon the said flange and thus gripping and holding said non-metal part.

2. The combination, in a horseshoe, of a leather part A, a metal stiffening part B secured thereto having enlarged rear ends, a rubber part C secured thereon and having heel portions with outer inclined surfaces, and an outer metal portion D having its rear ends formed to fit up onto the inclined heel portions of the rubber part C, said parts being so arranged that the heel portions of the rubber part are supported and strengthened by the part B so far as they project beyond said part D, substantially as shown and described.
3. The combination, in a horseshoe, of the sole-leather part A of substantially the form of the horse's hoof, a reinforcing narrow metal

part B having its heel ends enlarged, a rubber part C also having enlarged heel ends and 20 with a flange formed integrally therewith extending out around its outer edge, and a metal part D adapted to be superimposed upon said flange and thus reinforce and protect said rubber part C, said several parts being constructed, arranged and operating substantially as shown and described.

In witness whereof we have hereunto set our hands and seals, at Indianapolis, Indiana; this 30th day of December, A. D. 1899.

WILLIAM P. STRAWMYER. [L. S.]
OTTO NILIUS. [L. S.]
